UNITED STATES PATENT OFFICE.

LOUIS P. CALLAHAN, OF WESTFIELD, MASSACHUSETTS.

BODY-SUPPORTER.

1,164,338.

Specification of Letters Patent. Patented Dec. 14, 1915.

Application filed July 26, 1915. Serial No. 41,951.

To all whom it may concern:

Be it known that I, LOUIS P. CALLAHAN, a citizen of the United States of America, and resident of Westfield, in the county of 5 Hampden and State of Massachusetts, have invented certain new and useful Improvements in Body-Supporters, of which the following is a full, clear, and exact description.

This invention relates to a supporter for 10 the body and the same is particularly characterized by the inclusion therein of a vertical back member having opposite angularly extended and forwardly curved adjustable members to bear on the hips and back at opposite 15 sides of the spine and to support the back member clear of the spine, an abdominal band and means for its engagement with the back member and shoulder encircling members having connections with the back member at its upper part and at upper opposite 20 sides of the spine and to support the back member clear of the spine, an abdominal band and means for its engagement with the back member and shoulder encircling members having connections with the back member at its upper part and at upper opposite 25 sides of the spine and to support the back member clear of the spine, an abdominal band and means for its engagement with the back member and shoulder encircling members having connections with the back member at its upper part and at upper opposite 30 sides of the spine and to support the back member clear of the spine, an abdominal band and means for its engagement with the back member and shoulder encircling members having connections with the back member at its upper part and at upper opposite 35 sides of the spine and to support the back member clear of the spine, an abdominal band and means for its engagement with the back member and shoulder encircling members having connections with the back member at its upper part and at upper opposite 40 sides of the spine and to support the back member clear of the spine, an abdominal band and means for its engagement with the back member and shoulder encircling members having connections with the back member at its upper part and at upper opposite 45 sides of the spine and to support the back member clear of the spine, an abdominal band and means for its engagement with the back member and shoulder encircling members having connections with the back member at its upper part and at upper opposite 50 sides of the spine and to support the back member clear of the spine, an abdominal band and means for its engagement with the back member and shoulder encircling members having connections with the back member at its upper part and at upper opposite 55 sides of the spine and to support the back member clear of the spine.

B represents the abdominal band which has an engagement with the back member, and C C represent shoulder encircling members having connections with the back member at its upper part and also at opposite side portions thereof.

The vertical back member A is composed of facewise related longitudinally adjustable sections b and c, the section c being provided with a plurality of longitudinal slots d d through which bolts d², which are carried by, or through perforations in the section b are extended, said bolts having confining nuts. The back member A may, therefore, be lengthened and shortened so that the upper and lower pairs of bearing members a a may be positioned to suit the person of different wearers. The bearing members a a are laterally adjustable, and they also have swinging adjustments whereby their distension outwardly from the back member and the distance of their vertical separation may be such as to best adapt them to the person. As a provision for this capability the sectionally formed back member has bolts e e near the edge portions of its upper and lower ends; and it also has arc shaped slots f f, concentric with said bolts, e.

The forwardly curved and outwardly extended members have longitudinally aligned slots g, g², those g² being near the inner end of such members, while the ones g g are in outward relations thereto.

The aforementioned bolts e are passed through the outer slots g, and have confining nuts therefor.

The curved slots f intersect the inner slot g² so that the members a swinging on the loosened bolts e as fulcrums may be relatively adjustably moved for increasing or lessening the distance between the upper and lower sets of such members, and the parts may be held in their adjusted positions by the bolts or set screws h.

The abdominal band suitably widened at its central part has strap extensions i of loop shape, provided with take-up buckles or tie plates j, such as shown in face view and section in Figs. 3 and 4, and these strap extensions have clasp members k, k², one having a hook k³, and the other a slot k⁴ for the connection when the band is adjusted and carried around the abdomen, with each other, such clasp being at the back and having an engagement with the back member A.

One of the plates, the rearmost one, of the back member A is formed with upwardly opening and rearwardly offset tongues $m m$, and the aforementioned clasp members $k k^2$, have their lower edges angularly formed to provide shoulders o .

When the abdominal band is in place around the person, and the members k , k^2 of the clasp engage with each other, the 10 clasp overlies on the outer face of the back member A, and has an engagement within the tongues $m m$; and the shoulders o having edgewise engagements with the edges of the tongue-provided plate section, prevent 15 rocking of the clasp and hold it steady for the proper engagement of the band with the back member.

The shoulder encircling members C C have connections at p with the upper end 20 of the back member A to which they converge, and they also have connections at $q q$, with the back member at upper opposite side portions thereof. Both of the shoulder encircling members C are connected with a 25 plate s which by having a hook s^2 at its lower end is in substance a clasp and for the engagement with the back member A, by said hook s^2 the member A is provided with the horizontal slot s^3 . The ends of 30 the members C which are carried upwardly around the shoulders and downwardly under the arms to connections with the upper side portions of the back member A, receive their connections through means of the hook 35 ended clasp plate t , and the vertical slots t^2 in the back member.

The substantially flexible shoulder encircling members C C comprise flexible webbing or strap-like sections u and v , (the sections u terminating in the clasp members t and the sections v converging to and being connected with the clasp plate s) and the intermediate section w suitably curved and formed of metal or equivalent rigid 40 material. The sections $u u$ and $v v$ of the pair of shoulder encircling members formed looped or doubled as to the whole or portions of the lengths thereof are individually provided with take-up buckles or plates $x x$ 45 providing ample means for lengthening or shortening the encircling members as occasion or circumstances may require.

The back member A and the extension members or arms $a a$ may be advantageously 50 composed of aluminum, as also may the intermediate sections $w w$ of the shoulder encircling members C.

The abdominal band may be composed of 55 suitable fabric and stiffened in a desirable degree by having thereon or inclosed therewithin, a skeleton frame y of aluminum or other metal or material.

In applying the body support, the intermediate metallic or rigid members w are 60 brought to place to fit in the front of, and

under the arms, and the encircling members C are connected to the back member at the top and also at the upper side portions thereof,—the encircling members being adjusted as to length by the take-up buckles 70 or tie plates.

The abdominal band is brought to place around the body and fastened by the clasps which are inserted in their engagements with the upwardly open tongues m ,—the 75 strap-like terminals of the abdominal band being, of course, adjusted to proper length.

While being worn, the back member A will be supported by the curved extension members $a a$ on either side of the line of the 80 spine, under the shoulder blades and on the fleshy part of the hips at either side of the crupper bone.

While there is a very substantial support 85 on the body by the back member A, there is no strain on the spine while the effect of the appliance is to draw the abdomen into shape, increasing the chest expansion, straightening the shoulders and permitting the back bone to acquire increased strength 90 and natural position.

This appliance is especially beneficial for 95 the support of large abdomens, for the relief of weak backs, for materially correcting the curvature of the spine, sunken chests and round shoulders, and may be used to advantage in maternity cases and by those who have undergone surgical operations.

I claim:—

1. In a body support, a vertical back 100 member, having at upper and lower portions thereof opposite angularly extended and forwardly curved members to bear on the hips and back at opposite sides of the spine and to support the back member clear 105 of the spine, said back member being composed of plate sections vertically adjustable one on the other, and having means for confining said sections in their adjustments, and said oppositely extended members being 110 individually adjustable relatively to the back member both as to degree and the angularity of their extensions, and means for confining the oppositely extended members in the adjustments on the back members, an 115 abdominal band and means for connecting the ends thereof to the back member, and shoulder encircling members, having a plate to which they converge and have connection, said plate being detachably connected to the upper part of the back member, and the shoulder encircling members having 120 connections with the back member at upper opposite side portions thereof.

2. In a body support, a vertical back 125 member, having at upper and lower portions thereof opposite angularly extended and forwardly curved members to bear on the hips and back at opposite sides of the spine, and to support the back member clear of the 130

- spine, an abdominal band and means for connecting the ends thereof to the back member, and shoulder encircling members convergently arranged relatively to and detachably connected to the upper part of the back member, and having connections with the back member at upper opposite side portions thereof, and each said shoulder encircling member comprising flexible strap-like sections in the portions which connect with the back member, and an intermediate curved metallic section, for disposition at the portions of the body under the arms.
3. In a body support, a back member provided with upwardly opening and rearwardly offset tongues adjacent opposite edges thereof, an abdominal band having clasp plates at the ends thereof adapted to overlap the rear of the back member and to have engagements within said upwardly opening offset tongues, and having shoulders for engaging the back member and preventing rocking movements thereof relatively to such member, and shoulder encircling members, connected to the upper end and to opposite sides of the back member.
4. In a body support a back member consisting of facewise disposed plates, one of which has longitudinal slots, headed bolts passing through one of the plates and through the slots in the other and having confining nuts, forwardly curved members for bearing on the hips and back at opposite sides of the spine and supporting the back member clear of the spine, each said curved member having an outward adjustment relatively to the back member, and a swinging adjustment relatively thereto, and means for confining said curved members in adjusted positions on the back member, a band extending from engagement with the back member around the abdomen, and shoulder encircling members connected to the upper end and to the opposite sides of the back member.
5. In a body support, a back member consisting of longitudinally adjustable sections and said back member having bolts extended therethrough near the edge portions of its upper and lower ends, and also having arc shaped slots concentric with said bolts, forwardly curved members for bearing on the hips and back at opposite sides of the spine, each having longitudinally alined slots through the outer ones of which the aforementioned bolts are passed and the inner ones of which intersect the aforementioned curved slots in the back member, bolts passed through the intersecting slots, and confining nuts for the several bolts, a band extending from engagement with the back member around the abdomen, and shoulder encircling members connected to the upper end and to the opposite sides of the back member.
- Signed by me at Springfield, Mass., in presence of a subscribing witness.
